UNITED STATES PATENT OFFICE.

GEORGE MOORE, OF ERIE, PENNSYLVANIA.

VISE.

1,314,351.

Specification of Letters Patent. Patented Aug. 26, 1919.

Application filed February 21, 1919. Serial No. 278,332.

To all whom it may concern:

Be it known that I, GEORGE MOORE, a citizen of the United States, residing in the city of Erie and State of Pennsylvania, 5 have invented new and useful Improvements in Vises, of which the following is a specification, reference being had to the accompanying drawings.

This invention pertains to vises for the 10 use of mechanics of all kinds, and the principal object is to produce a quick adjustable vise, one which may be quickly and positively adjusted to the work with the least loss of time.

15 Another object is to produce such a vise in a comparatively simple form, and which will be practical and efficient in use.

With these objects in view, attention is called to the accompanying drawings, 20 wherein—

Figure 1 is a sectional side elevation, showing the vise properly mounted upon a work-bench;

Fig. 2, a detail of the outer jaw, showing 25 the method of pivotally mounting same at the end of the guide bar;

Fig. 3, a detail of the guide-ways mounted below the bench, and in which the guide bar slides;

30 Fig. 4, a detail of the screw bar;

Fig. 5, a detail of the screw lever which works upon the end of the screw bar;

Fig. 6, a detail of the lock plate which is mounted underneath the work-bench immediately over the screw bar, and which carries the inner jaw at the outer end thereof.

Referring more particularly to the drawings, the purpose of my invention is to produce 40 a vise, the jaws of which may be instantly adjusted against the work by merely sliding the guide bar and outer jaw inwardly until the outer jaw comes in contact against the work.

45 To accomplish this object, I provide a guide-bar 1 which is slidingly mounted within the guide-ways 2, said guide-ways being in turn rigidly mounted and properly spaced beneath the work bench 3. The 50 guide bar 1 is provided on its upper surface with one or more angular recesses 4, said angular recesses being formed with the sides

5 perpendicular to the axis of the guide bar 1, and with the sides 6 sloping forwardly from the sides 5. Complementary to this 55 guide bar 1, I provide a lock bar 7, same having formed on its under side angular recesses 8 with perpendicular sides 9, and sloping sides 10 exactly reversed to the perpendicular sides 5 and sloping sides 6 60 formed on the guide bar 1, as aforesaid; and so that the resulting teeth 11 of the lock bar 7 will fit into the recesses 4 of the guide bar 1 and will abut against the reversed teeth 12 formed on the guide bar 1. 65 Along the upper side of the lock bar 7, I cut a series of lock notches 13, which may be made of any suitable size and shape, depending upon the character of work the vise is to perform; that is to say, whether 70 it is to be used as a machinist's vise, or a woodworker's vise, or otherwise. These lock notches 13 correspond to a complementary series of notches 14 cut on the lower side of the lock plate 15. The recesses 4 and 75 8 form vertical shoulders and inclined bottom faces and the shoulders are of a height greater than the height of the shoulders or projections formed by the notches 13 and 14, so that a longitudinal movement of the 80 locking bar incident to an operation of the vise tightening means will carry the notches 13 and 14 into and out of engagement with each other without disengaging the teeth formed by the recesses 4 and 8. This lock 85 plate 15 is screwed or otherwise secured to the under side of the work bench 3, and said lock plate 15 carries at its outer end the rigidly mounted inner jaw 16. The lock bar 7 is bored longitudinally and screw- 90 threaded as shown at 30, so as to engage the screw threads 31 formed on the screw bar 28. Upon the outer end of the guide bar 1, I pivotally mount the outer jaw 17.

In the construction shown, the outer jaw 95 17 is formed with a slot 18 cut through the lower side thereof, and adapted to set over the end of the guide bar 1, and a pivot pin 19 is set through the outer jaw 17, and passes through the end of the guide bar 1, 100 thus giving the outer jaw 17 the pivotal connection with the guide bar 1 referred to. A stop pin 20 may be set in the outer end of the guide bar 1 to prevent the outer jaw

from swinging too far outwardly. The outer jaw 17 is likewise pierced with the screw bar hole 21 to admit the outer end of the screw bar 28, and the outer face of this screw bar hole 21 is preferably curved or concaved inwardly, as shown at 22, to accommodate the rocking motion of the convexed end 32 of the lever cap 24.

5 A thread 23 is cut around the outer end of the screw bar 28, and upon this end is mounted the lever cap 24, same being formed with an interior thread 25 to correspond to the thread 23, as aforesaid. Through the lever cap 24 is formed a hole 10 26 through which is passed the lever 27.

15 In operation, it will be noted that with the vise properly mounted upon the work bench as described, the outer jaw 17 may be slid back against the work 29 located 20 between the two jaws, by one motion of the hand, after which the lever 27 being turned up, the result is to force the lock bar 7 vertically upward against the lock plate 15, and so that the teeth 11 interlock 25 with the teeth 12, thereby locking the lock bar 7 firmly in place, after which as the lever 27 is further turned, the outer jaw 17 is forced down against the work 29, and locks the work in position.

30 It will be seen that I have here provided a simple, practical and efficient vise for the purpose described, and one which may be readily and quickly adjusted in use.

While I have herein described a certain 35 specific manner and method of constructing the elements of my invention, it is understood that I may vary from the same in minor details, not departing from the spirit of my invention, so as best to construct a 40 practical device for the purpose intended, as defined in the appended claims.

What I claim to be new and patentable is:

1. A vise for quick adjustment comprising 45 a slidable bar provided at its upper face with recesses forming shoulders and inclined faces, means for guiding the slidable bar, a fixed locking member located above and in spaced relation with the slidable bar and provided at its lower face with notches, a 50 movable jaw carried by the slidable member, a movable locking member operating between the slidable bar and the fixed locking member and provided at its lower face with recesses corresponding with the recesses of 55 the slidable bar, said movable locking member being also provided at its upper face with notches corresponding with the notches of the fixed locking member, the inclined faces formed by the recesses permitting the 60 movable locking member to engage with and disengage from the fixed locking member when the said movable locking member is moved longitudinally of the slidable member and adjusting means connecting the said 65 jaw with the movable locking member and

adapted to successively operate the said movable locking member and also the movable jaw.

2. A vise for quick adjustment, comprising 70 guide-ways; a slidable guide bar mounted therein carrying a plurality of comparatively large, right-angled notches on its upper side, said notches sloping upwardly and forwardly; a screw bar carrying a plurality of notches on its lower side complementary 75 to and meshing with the notches on the guide-bar, and carrying on its upper side a plurality of relatively small lock notches, and having a screw-thread cut at its outer end; a lock-plate carrying on its under side 80 a plurality of lock notches complementary to and meshing with the lock notches on the screw-bar, and having a rigidly mounted inner jaw at its outer end; an outer jaw pivotally mounted from the outer end of the 85 guide bar and having a central hole for the end of the screw-bar; and a screw-lever rotatively mounted on the threaded end of the screw-bar.

3. A vise for quick adjustment comprising 90 a fixed locking member having a stationary jaw and provided at its lower face with a longitudinal series of notches, side plates secured to and depending from the said locking member and provided with 95 guiding grooves, a slidable member located between the side plates and guided by the said grooves and provided in its upper face with recesses forming shoulders and inclined faces, a movable locking member operating 100 between the slidable member and the fixed locking member and provided at its upper and lower faces with notches and recesses corresponding to the notches and recesses of the fixed locking member and the slidable 105 bar, a movable jaw carried by the slidable member and adjusting means connecting the movable jaw with the movable locking member and operating successively the movable locking member and the said movable jaw. 110

4. In combination with a work bench, a vise for quick adjustment, comprising 115 guide-ways rigidly mounted under the bench; a guide-bar slidably mounted in the guide-ways, said guide-bar being formed with a 120 series of notches cut on its upper side with the hypotenuse of each notch sloping upwardly and forwardly; a frontal jaw pivotally mounted at the outer end of the guide-bar and having a central hole cut transversely through; a screw bar slidably mounted above the guide-bar with its outer end projecting through the hole in the outer jaw, a screw thread cut on said end, a series of notches cut on its lower side, same being 125 formed complementary to and to mesh with the notches on the guide-bar, and a series of smaller lock-notches cut on the upper side thereof; a lock-plate rigidly mounted on the under side of the bench immediately over 130

the screw bar, said lock-plate having a series of lock-notches cut on its under side to mesh with the lock-notches on the screw-bar; an inner jaw rigidly mounted at the outer end of the lock-plate; a screw-cap with an interior thread to mesh with the thread on the outer end of the screw bar and rotatively

mounted thereon; and a lever arm connected to said screw-cap.

GEORGE MOORE.
